ATTORNEY

UNITED STATES PATENT OFFICE.

JACOB KAUFMANN, OF PHILADELPHIA, PENNSYLVANIA, ASSIGNOR TO STEEL HEDDLE MANUFACTURING COMPANY, OF PHILADELPHIA, PENNSYLVANIA, A CORPORATION OF PENNSYLVANIA.

LOOM-HARNESS.

1,093,995.

Specification of Letters Patent. Patented Apr. 21, 1914.

Application filed January 6, 1912. Serial No. 669,788.

To all whom it may concern:

Be it known that I, JACOB KAUFMANN, a citizen of the United States, residing at Philadelphia, in the county of Philadelphia 5 and State of Pennsylvania, have invented certain new and useful Improvements in Loom-Harness, of which the following is a specification.

My invention relates to loom harness and 10 it has more particular relation to the means for attaching the jack cords or straps or other actuating means to the heddle frames.

The principal object of my invention is to 15 provide a simple and efficient device where- by the cords or straps for actuating the heddle frames may be quickly and easily attached thereto, and which device is so constructed and arranged as not to cut or chafe the loop of the cord or strap.

20 My invention also contemplates means for attaching the cord or strap whereby the same will not pull out from the top and bottom bars of the heddle frames, as frequently occurs where the ordinary screw hooks or eyes 25 are used for this purpose.

The nature and characteristic features of 30 my invention will be more readily understood from the following description taken in connection with the accompanying drawings forming part hereof, in which—

Figure 1 is a front elevation of a heddle frame and its actuating jack cord with the device of my present invention shown in connection therewith; Fig. 2 is a transverse section enlarged of the upper bar of the heddle frame shown in Fig. 1 with one of the connecting devices mounted thereon, the section being taken on the line 2—2 of Fig. 1; Fig. 3 is a front elevation of one of the connecting devices detached; Fig. 4 is a plan view of one of the connecting devices opened or flattened out to illustrate more clearly certain features of my present invention; Fig. 5 is an enlarged sectional view of the upper 45 end of one of the connecting devices taken approximately on the line 5—5 of Fig. 3.

Referring to the drawings, in the particular embodiments of my invention therein shown, 8 is the heddle frame of any of the 50 usual types, but which as shown may consist of the top and bottom bars 9 connected by the side bars 10, which in turn support the heddle rods 11 upon which the heddles 12 are mounted. The top and bottom bars 55 9 are usually made of flat lumber having

rounded edges. The jack cords 13 are connected to the top and bottom bars 9 by means of the devices 14 comprising my present invention.

The connecting device 14 consists of a thin flat strip of metal preferably of a spring like steel a portion 15 of which is bent to conform to the general shape of the frame bars 9 as clearly shown in Fig. 2 of the drawings, and from the outer edge of said bar 9 the two ends of the strip 14 converge as at 16 and then extend in contiguous relationship as clearly shown in said Fig. 2. The contiguous ends 17 of the strip 14 are each provided with a central slot 18. In the form shown in the drawings the slot continues in inclined direction to the side margin of said strip. It should be noted that the inclined portions 19 of the slots 18 of each of the respective ends extend to the opposite sides of the strip 14 for a purpose to be presently explained. A portion of the metal from the slot 18 is bent outwardly and curled back as at 20 to the outer surface of the strip so as to provide rounded bearings 21 for the loop of the jack cord 13, which construction is clearly shown in Fig. 5 of the drawings.

It will be seen that there is thus provided a simple and efficient device for attaching the jack cord or strap to the heddle frame which will not pull out or become detached notwithstanding the rough usage to which devices of this character are subjected, and that on account of the bent over lip 20 there will be provided rounded bearings 21 at the outer end of the slot 18 which will prevent chafing or cutting of the jack cord or strap. Furthermore, in the forms shown the jack cord may be quickly and easily attached without untying the loop by merely springing apart the contiguous ends 17 of the fastening device 14 and passing the loop through the inclined portion 19 of the slot, first on the one side and then on the other, after which, when the strain is on the structure, the ends 17 will be held in close relationship by the loop of the jack cord, and the inclined open end 19 of the slot 18 of each end portion 17 will be closed by the lapping over of the soiled portion of the other contiguous end portion 17 as clearly shown in Fig. 3 of the drawings.

Having thus described the nature and characteristic features of my invention what

2
I claim as new and desire to secure by Letters Patent is:—

A device of the character described comprising a strip of metal surrounding the heddle frame bar, said strip having its ends brought together and having slots in said ends for engagement by the jack cord or strap, said slots having continuations extending to the side margins of the strip, the continuation of the slot in one end of the strip extending to the opposite side to that to which extends the continuation of the

slot in the other end of the strip, and the metal from said slots being curled over on the outer faces of the ends of the strip to 15 thereby provide rounded bearing portions at the ends of the slots.

In testimony whereof, I have hereunto signed my name in the presence of two witnesses.

JACOB KAUFMANN.

Witnesses:

ALBERT HELLWIG,
ROBT. J. FREITAG.
